UNITED STATES PATENT OFFICE.

STEWART HARTSHORN, OF NEWARK, NEW JERSEY, ASSIGNOR TO STEWART HARTSHORN COMPANY, OF EAST NEWARK, NEW JERSEY, A CORPORATION OF NEW JERSEY.

SHADE-ROLLER.

1,202,288.

Specification of Letters Patent. Patented Oct. 24, 1916.

Application filed April 30, 1915. Serial No. 24,856.

To all whom it may concern:

Be it known that I, STEWART HARTSHORN, a citizen of the United States, resident of the city of Newark, county of Essex, State 5 of New Jersey, have invented a certain new and useful Shade-Roller, (Case C,) of which the following is a specification.

This invention relates to shade rollers of the type in which the shade is attached to 10 the roller by means of clips engaging with a groove in the roller.

The invention is particularly applicable for use in connection with the fastening means disclosed in my two applications for 15 Letters Patent, specifications executed on even date herewith, entitled Shade roller, Serial Number 24,854, and Shade roller, Serial Number 24,855.

The object of the invention is to make a 20 strong, rigid and very cheap shade roller having a dovetailed groove extending from end to end.

Another object is to reduce the number of 25 parts of which the roller is made and the number of joints necessary to secure the parts together.

These and further objects will more fully 30 appear from the following specification and accompanying drawings, considered together or separately.

In the drawings, Figure 1 is a perspective view of a portion of a shade roller embodying the invention; Fig. 2 is an end view of the same, on an enlarged scale.

35 In all views like parts are designated by the same reference characters.

Referring to the drawings, particularly Figs. 1 and 2, the roller 1 is shown as formed of sheet metal. The sheet is bent 40 to cylindrical form. The greater part of the perimeter of the roller is smooth and curved, as shown. The portion marked 2 is an area which is noncylindrical. This area is coterminous with the groove 3. The 45 groove is formed by means of the trough 4. In the embodiment chosen for illustration the trough has a flat bottom 5 and inclined sides 6 and 7. The trough is integral with

the wall of the roller 1. The trough is therefore made by bending the sheet to zig-zag 50 shape to define the sides and bottom of the groove. In the embodiment chosen for illustration and shown in Figs. 1 and 2, the joint of the two over-lapping edges of the roller is adjacent to the side 6. To constitute this joint the edge of the curved part of the roller is creased, forming a flap 8. This flap is bent to assume a position substantially parallel with the side 6 of the trough and is secured thereto by solder or 60 other suitable fastening means. The width of the flap 8 is substantially the same as the width of the other side 7 of the trough so that a symmetrical groove 3 with sides 65 the same width is produced.

Associated with the cylinder hereinbefore described are end plates 11 having a pin or pins 12 therein for engagement with the roller supporting brackets. These end plates may be made of any suitable material and 70 shape.

In accordance with the provisions of the patent statutes, I have described the principle of my invention, together with the apparatus which I now consider to represent the best embodiment thereof; but I desire to have it understood that the apparatus shown is merely illustrative and that the invention may be carried out in other ways.

Having now described my invention, what I claim as new and desire to secure by Letters Patent, is:

1. A shade roller formed of a single plate of sheet metal bent to substantially cylindrical shape, one edge of the sheet being bent to form a dovetail trough having a flat bottom, the other edge of the sheet being bent to form a flap on an acute angle to the plate, said flap resting within the trough 85 and in contact with the flap forming the free wall of the trough, the end of the flap abutting against the bottom of the trough 90 to form a smooth surface therein.

2. A shade roller formed of a single plate 95 of sheet metal bent to substantially cylind-

drical shape, one edge of the sheet being bent to form a dovetail trough having a flat bottom, the other edge of the sheet being bent to form a flap on an acute angle 5 to the plate, said flap resting within the trough and in contact with the flap forming the free wall of the trough, the end of the flap abutting against the bottom of the

trough to form a smooth surface therein, and means for securing the flaps together. 10

This specification signed and witnessed this 28th day of April, 1915.

STEWART HARTSHORN.
